CHANGE-OVER MECHANISM FOR VALVES,
ESPECIALLY SUCH OF DRY GAS-METERSMax Helm, Berlin-Niederschönhausen, Germany,
assignor to Allgemeine Elektricitäts-Gesell-
schaft, Berlin, GermanyApplication July 5, 1935, Serial No. 30,027
In Germany June 19, 1934

4 Claims. (Cl. 74—97)

There exist valve change-over devices for gas-meters, in which the change-over valve lever contacts with lugs or segments and is guided by them until the moment of the changing-over of the valves so that the changing-over itself takes place very quickly by means of a spring. Said segments lock the change-over lever by their contact with it and thereby hold the closed valve firmly down on its seat so that premature opening is prevented.

Valve change-over devices of the above-mentioned type operate satisfactorily at a certain definite load of the gas-meter. If, however, the load increases, the diaphragm of the gas-meter moves a greater distance so that also the member bearing the lugs or segments, for instance a disk affixed to a shaft turned to and fro by the diaphragm of the gas-meter, is caused to turn through a larger angle. In such a case, the change-over lever of the valve may not contact the said segments and be temporarily without any guidance, in consequence whereof it may further occur that the closed valve is pressed upon its seat not firmly enough and, therefore, gas can escape also through this valve, whereby the measuring accuracy of the gas-meter is considerably impaired. The change-over valve lever, for some cause, for instance owing to jamming, the presence of dirt, or to slackening of the change-over spring, or the like, after having partly changed over, turns in the reverse direction, i. e. rearwardly, and remains hanging in an intermediate position so that both valves are open at the same time and no measuring at all takes place.

The present invention relates to a valve change-over device intended especially for use in connection with dry gas-meters and being so designed as to prevent the above disclosed drawback in the case of over-loading. The gist of the invention resides therein that, besides the lugs or segments, also a locking device is provided which after the change-over has taken place, retains the change-over valve lever in its new position until it is guided by a lug concerned. The invention presents the advantage that even in the case of the overloading and the corresponding larger angular movement of said lever this latter is securely prevented from swinging back in the direction of its former position and is then retained in an intermediate position. In my improved device the change-over lever is always held fast in the one or the other of its two end positions as long as it is not guided by its associated lug or segment. The valves are always

either completely open or completely closed, so that gas can flow only through that valve which is open at the time being. The measuring accuracy and the reliability of the gas-meter is thereby considerably increased and rendered completely independent of the load on the gas-meter at that time.

The invention is illustrated diagrammatically and by way of example on the accompanying drawing which shows several constructional forms especially of the locking device. There are in all these forms two lugs or segments, but other constructions are possible. Essential in each case is that the change-over valve lever is held fast either by the segment or by a locking device designed according to this invention, the segment and the locking device alternating in holding fast said lever, which, therefore, is always located in the one or the other of its end positions.

The gas-meter proper and the diaphragm which forms a part of it have been omitted in the drawing.

Fig. 1a is a front-view of a change-over device designed according to this invention, the parts being shown in the position they assume just prior to the changing-over.

Fig. 1b is a similar representation, a few portions of Fig. 1a being omitted in this figure and the parts being shown in that position which they assume just after the changing-over.

Fig. 1c is a plan of part of the device, the position of the parts corresponding to that of Fig. 1a.

Figs. 2a, 2b, and 2c are views similar to those of Figs. 1a, 1b, and 1c and show a modification, the positions of the parts in the three figures corresponding with those of Figs. 1a—1c.

Figs. 3, 3a, and 3b are views similar to those of Figs. 1a, 1b, and 1c, and show another modification the position of the parts corresponding likewise with Figs. 1a, 1b, and 1c, and

Fig. 4 is a representation of still another constructional form, all as fully described herein-after.

Referring to Figs. 1a, 1b, and 1c, 1 denotes a shaft turned in a known manner by the diaphragm of the gas-meter through an angle, the size of which depends upon the load on said meter. Attached to the free end of said shaft is a circular disk 2 from which project, two oppositely located lugs or segments 3 and 3'. 4 denotes the change-over valve lever which is affixed to a shaft 5 (Fig. 1a) connected with the valves (not shown) of the gas-meter and actuating, i. e. changing-over, them. At the lower end of said lever is a transverse member 6 which is

provided with two guide noses 7 and 7' directed towards said segments 3 and 3', as appears from Fig. 1c. A plate spring 8 (Fig. 1a) is attached at its upper end to the upper end of the lever 4 by means of a pin 9 or the like, and therebelow the spring is guided between two pins 10. On the disk 2 is a projecting arm 12 bearing a turnable and slotted pin 11 through the slot of which the free end of the spring 8 slidably extends.

10 In Fig. 1c the spring 8 has been omitted.

On the outer side of the transverse member 6 is a wedge-shaped projection 13 having two oppositely located oblique surfaces 14 and 15 (Fig. 1c) which are moved alternately to the left and 15 to the right together with, and by, the lever 4, according to the direction of motion of the same. Said surfaces 14 and 15 co-operate with a roll 19 attached to the free end of an arm 17 hinged at the point 16 to a stationary part of the gas-meter, and there is also provided a helical tension 20 spring 18 holding the roll 19 always in contact with the wedge shaped member 13. The spring 8 when tensioned is strong enough to overcome the resistance offered by friction and the parts 25 13, 19.

The manner of operation of this device is as follows:

In the position of the parts as shown in Fig. 1a the lever 4 is in a position in which the guide nose 7' is just being disengaged from the lug or segment 3'. Immediately thereafter the tension of the spring 8 becomes active, the spring straightens and turns the lever 4 with the transverse member 6 and the wedge 13 from the position of 30 Fig. 1a into the position of Fig. 1b, whereby the shaft 5 to which the lever 4 is secured is turned, the extent of this motion being such that one of the two valves (not shown) is closed and the other is opened.

40 If in consequence of over-loading the dia-phragm of the gas-meter has turned the shaft 1 (Fig. 1c) with the disk 2 and segments 3, 3' to such an extent that the guide-nose 7 cannot reach and contact the segment 3, then the lever 45 4 will not be retained by this segment in this position. In such circumstances this is now effected by the wedge 13 and the arm 17 with its roll 19, because the wedge 13 will move below said roll from the right to the left, bringing the roll upon the oblique surface 14. It will be obvious 50 that the lever 4 will now be retained in the position shown in Fig. 1b without the assistance of the segment 3. As soon as the disc 2 has rotated for a certain angle, the guide-nose 7 engages on the segment 3 which takes over the guiding and locking of the lever 4.

55 These phases of operation are repeated at every changing-over, the only difference being that the disc 2 is turned alternately in clock-wise direction and reversely thereto.

In the modification shown in Figs. 2a-2c, the locking device is formed by two angularly disposed plate springs 20 and 20' affixed to the lever 4 and provided at their lower ends with inwardly 65 directed pins 21 and 21', each of which has an oblique end-surface 22, as in Fig. 2c. In Fig. 2a the position of the parts is that which they assume immediately prior to the changing-over of the valves. There are segments 3 and 3' and 70 guide noses 7 and 7' like those in Figs. 1a-1c. The pins 21, 21' are above the noses 7, 7' so that said pins will not engage the segments 3, 3' when the lever shifts. In Fig. 2a the guide nose 7' is just being disengaged from the segment 3'. In Fig. 75 2b the parts are in the position they assume im-

mediately after the changing-over, the guide nose 7 having not yet become engaged with the segment 3 by reason of the larger angular movement of the disk 2. In this position of the parts the changing-over lever 4 is retained by the locking device, in that the oblique end face 22 of the pin 21 has slipped over the segment 3 and has snapped in therewith, whereby the lever 4 is prevented from turning back into its former position. The parts remain in the position shown 10 in Fig. 2b until, owing to a counterclockwise movement of the disk 2, the guide nose 7 engages upon the segment 3 which now acts as guide member.

In the constructional form illustrated in Figs. 15 3a-3c the lever 4 is equipped at its lower end with a T-shaped plate spring 23, the laterally extending free ends 23', 23'' of which are so arranged and bent off and of such a size that when the parts are moved during a changing-over opera- 20 tion from the position in Fig. 3a into the position in Fig. 3b the spring end 23'' slides elastically over the segment 3' (from the right to the left) and engages its inner side so that the lever 4 is locked in its other position, until the guide nose 7 25 has become engaged with the segment 3. The spring ends 23', 23'' are above the guide noses 7, 7' so that said ends 23, 23' will not engage segments 3, 3' when the lever shifts. The spring 23 30 must be so weak that the shifting of the lever by the spring 8 is not hindered.

In the further modification shown in Fig. 4 the locking device consists of two bell-crank levers 24 and 24' that are loosely supported upon the shaft 1 which, as has already been mentioned 35 in a preceding part of this specification, is turned to and fro by the gas-meter diaphragm. The bell-crank lever 24 comprises an upwardly directed arm 25 and a laterally directed arm 27, and the bell-crank lever 24' similarly comprises 40 two arms 25' and 27'. The arms 25 and 25' are connected with one another by a helical tension spring 26. Near the free end of each of the arms 27, 27' is a projection 28, the shape and size of which is such that after every changing-over the 45 respective guide nose 29 or 29' of the lever 4 is retained by the projection 28 until that guide nose has become located upon the corresponding segment concerned which latter now acts as guide member. The projections 28 are always engaged 50 by the segments or lugs 3, 3' except when the bell cranks are depressed by the noses 29 and 29'. In Fig. 4 the parts are in the position they have assumed immediately after the changing-over has taken place. The right-hand guide nose 29' of 55 the change-over lever 4 has just left the lug 3'; the left-hand guide nose 29 has not yet arrived upon the lug 3, but is retained by the projection 28 of that side, upon which it has arrived. The segments 3 and 3' are shown in the drawing as 60 being in the shape of segmental wedges, however, these elements may also have the same form as the segments 3 and 3' in the other figures. Owing to the tension of the spring 26 the bell-crank lever 24 contacts with, and is retained by, the 65 lug 3 (position shown in Fig. 4). At every changing-over a guide-nose concerned depresses the respective bell-crank lever and snaps in behind the corresponding projection 28 so that the lever 4 is again reliably held fast in its new position until 70 the corresponding lug concerned acts as guide member.

I claim:—

1. A change-over mechanism for valves, particularly for dry gas meters, comprising in com- 75

5 bination a change-over lever shiftable between two different end positions, guide noses on said lever, an oscillating disc adapted to control the shifting of said lever, a shaft on which said disc is arranged and which is oscillated by the dia-
10 phragm of the gas meter, segments on said disc adapted to engage said guide noses, a spring connecting said lever and disc and adapted to shift the lever from one to the other of its end positions,
15 10 and a locking device for retaining said noses in their respective end positions until engaged by the cooperating segment.

20 2. A change-over mechanism for valves, par-
ticularly for dry gas meters, comprising in com-
bination a change-over lever shiftable between
25 two different end positions, guide noses on said
lever, an oscillating disc adapted to control the
shifting of said lever, a shaft on which said disc
is arranged and which is oscillated by the dia-
phragm of the gas meter, segments on said disc
30 adapted to engage said guide noses, a spring
connecting said lever and disc and adapted to shift
the lever from one to the other of its end positions,
35 and a locking device for retaining said
noses in their respective end positions until en-
gaged by the cooperating segment, said locking
device comprising a pin attached yieldingly to the
change-over lever and having an oblique end
face adapted to slide over the cooperating seg-
ment when arriving in the new position during
the changing over, said end face contacting then
with the outer surface of said segment.

35 3. A change-over mechanism for valves, par-
ticularly for dry gas meters, comprising in com-
bination a change-over lever shiftable between
two different end positions, guide noses on said

lever, an oscillating disc adapted to control the shifting of said lever, a shaft on which said disc is arranged and which is oscillated by the dia-
10 phragm of the gas meter, segments on said disc adapted to engage said guide noses, a spring connecting said lever and disc and adapted to shift the lever from one to the other of its end positions, and a locking device for retaining said noses in their respective end positions until engaged by the cooperating segment, said locking device com-
15 prising a plate spring attached to said change-
over lever in such a position that an end of the
spring slides from the outer to the inner side of
the cooperating segment.

20 4. A change-over mechanism for valves, par-
ticularly for dry gas meters, comprising in com-
bination a change-over lever shiftable between
25 two different end positions, guide noses on said
lever, an oscillating disc adapted to control the
shifting of said lever, a shaft on which said disc
is arranged and which is oscillated by the dia-
phragm of the gas meter, segments on said disc
30 adapted to engage said guide noses, a spring con-
necting said lever and disc and adapted to shift
the lever from one to the other of its end posi-
tions, and a locking device for retaining said
noses in their respective end positions until en-
35 gaged by the cooperating segment, said locking
device comprising two bell-crank levers pivoted
on said shaft, each of said bell-crank levers having
two arms of which one on each lever has a
projection adapted to cooperate with the corre-
sponding guide nose, and a spring connecting the
other arms of said bell crank levers.
